UNITED STATES PATENT OFFICE.

MATTHEW B. HITZEMANN, OF HUTCHINSON, KANSAS.

DESIGN FOR A SIGNAL CASING.

Application filed October 19, 1927. Serial No. 23,794. Term of patent 3½ years.

To all whom it may concern:

Be it known that I, MATTHEW B. HITZEMANN, a citizen of the United States, residing at Hutchinson, in the county of Reno and State of Kansas, have invented a new, original, and ornamental Design for a Signal Casing, of which the following is a specification, reference being had to the accompanying drawing, forming a part thereof.

Figure 1 is a front elevation of a signal casing showing my new design.

Figure 2 is a side elevation thereof.

I claim:—

The ornamental design for a signal casing, as shown.

MATTHEW B. HITZEMANN.
